UNITED STATES PATENT OFFICE.

ALBERT W. HAM, OF LANSINGBURG, ASSIGNOR TO THE TROJAN BUTTON FASTENER COMPANY, INCORPORATED, OF TROY, NEW YORK.

BUTTON-FASTENER PACKAGE.

SPECIFICATION forming part of Letters Patent No. 537,531, dated April 16, 1895.

Application filed November 26, 1894. Serial No. 529,944. (No model.)

To all whom it may concern:

Be it known that I, ALBERT W. HAM, of the village of Lansingburg, county of Rensselaer, and State of New York, have invented new and useful Improvements in Button-Fastener Packages, of which the following is a specification.

My invention relates to a button-fastener package adapted to contain button-fasteners to be sold as merchandise with the package case adapted by its construction to transfer the fasteners which it contains to the slide-way or chute of a tube-loading machine, wherein the fasteners are threaded into the eyes of buttons, for use in button-setting machines; and it is one of the objects of my invention to dispense with that part of a tube-loader mechanism by which the fasteners are transferred from a hopper to a slide-way which the fasteners straddle, and on which they slide down under the influence of gravity to where they are threaded into the eyes of buttons and transferred to a tube to attach to a button-setting machine. To adapt fasteners to a particular button setting machine requires that they should be made accurately as to size, bend, and shape to suit the machines for which they are designed; and to limit the user to the employment of proper fasteners and to prevent the use of badly formed imitations of them is another object of my invention; and these results I accomplish by the construction and arrangement of the button fastener package hereinafter described.

The fastener package herein shown and described is more particularly adapted for use in connection with the tube-loader mechanism described in an application for Letters Patent made by me and filed in the United States Patent Office November 26, 1894, and known as Serial No. 529,943, although the package may be used in connection with any tube-loading mechanism having a blade-form slide-way whereon the fasteners straddle to slide down by gravity.

Accompanying this specification to form a part of it there is a plate of drawings containing five figures illustrating my invention with the same designation of parts by letter reference used in all of them.

Of the illustrations Figure 1, is a perspective of my improved button fastener package. Fig. 2, is another perspective of the case showing its form before the fasteners are inserted, 55 the ends bent inwardly to retain them, and the top bent down. Fig. 3, is a section taken on the line x', x' , of Fig. 1. Fig. 4, is a section taken on the line x^2, x^2 , of Fig. 1, and Fig. 5, is a section taken crosswise of the 60 package after having been passed on over the slide-way of a tube loading machine to transfer the fasteners thereto.

The several parts of the package thus illustrated and the function of the parts are designated by letter reference and the function of the parts is described as follows:

The letter P, designates the package as filled and prepared for selling as merchandise.

The letter C, designates the case which has 70 a flattened tube-form and it is produced from sheet metal preferably sheet tin. It has flat sides S', S², the bottom B, and the top T, with the latter on its open edge overlapping the adjacent side. The fasteners F (generally 75 one gross) are placed in the package case so as to straddle the side S². Then the latter is bent inwardly as shown at e^2, e^2 , of Fig. 1, at each end, and the top T, is bent down over the fasteners. When it is desired to transfer 80 these fasteners to the blade-form slide-way of a tube loading machine, the package is passed on over the slide-way of the tube-loader with the prongs of the fasteners where outside of the case side S², straddling the slide-way W, as 85 shown at Fig. 5. While in this position, the top T is bent upwardly and the case dropped, it leaving the fasteners upon the slide-way of the tube-loader. Where there is combined with a tube-loader, a fastener hopper, the 90 number of working parts is increased, and the chances of getting out of order are increased, and this contingency is by the use of my improved fastener package, thus made, avoided.

While I have shown my case made to receive staple-form fasteners, it may be used to contain other fasteners containing prongs, and which are caused to descend on a slide-way to the point whereat they are threaded 95 into the buttons.

Having thus described my invention, what

I claim, and desire to secure by Letters Patent, is—

5 A package for containing button fasteners having a flat tube-form with its sides connected with its bottom and its top connected to one of its sides and constructed to overhang the edge of the other side, and to be bent inwardly at the ends and top to retain button-fasteners arranged therein, substan-

tially in the manner as and for the purposes so set forth.

Signed at Troy, New York, this 21st day of November, 1894, and in the presence of the two witnesses whose names are hereto written.

ALBERT W. HAM.

Witnesses:

W. E. HAGAN,

CHARLES S. BRINTNALL.
